United States Patent

Des. 241,717
Patented Oct. 5, 1976

241,717

DRUM

Edward J. Chase and William R. Topper, Newark, Del.,
assignors to Container Corporation of America,
Chicago, Ill.

Filed Aug. 29, 1974, Ser. No. 501,510

Term of patent 14 years

Int. Cl. D9—02

U.S. Cl. D9—170

FIG. 4

FIG. 5

FIG. 1 is a top plan view of a drum showing our new design;

FIG. 2 is a side view looking in the direction of the line 2—2 of FIG. 1;

FIG. 3 is a side view looking in the direction of the line 3—3 of FIG. 1;

FIG. 4 is a sectional view taken on the line 4—4 of FIG. 2; and

FIG. 5 is a sectional view taken on the line 5—5 of FIG. 2.

We claim:

The ornamental design for a drum, as shown.
